Clarence M^cC. Eveleth
Inventor

UNITED STATES PATENT OFFICE.

CLARENCE McCLELLAN EVELETH, OF PLYMOUTH, NEW HAMPSHIRE.

WEATHER-STRIP.

SPECIFICATION forming part of Letters Patent No. 609,798, dated August 30, 1898.

Application filed January 18, 1897. Serial No. 619,657. (No model.)

To all whom it may concern:

Be it known that I, CLARENCE McCLELLAN EVELETH, a citizen of the United States, residing at Plymouth, in the county of Grafton 5 and State of New Hampshire, have invented a new and useful Door Attachment, of which the following is a specification.

My invention relates to weather-strip attachments particularly adapted for doors, and 10 has for its object to provide a simple, compact, and efficient construction and arrangement of parts mounted upon and inclosed within a frame forming a part of the attachment and adapted as an entirety to be countersunk or fitted in a longitudinal groove or 15 kerf formed in the edge of a door.

Further objects and advantages of this invention will appear in the following description, and the novel features thereof will be 20 particularly pointed out in the appended claims.

In the drawings, Figure 1 is a longitudinal sectional view of an attachment constructed in accordance with my invention applied in 25 the operative position to the lower edge of a door. Fig. 2 is a perspective view of the casing or frame of the attachment. Fig. 3 is an end view of the weather-strip arranged in its operative position. Fig. 4 is a detail view, 30 partly in section, of the connection between the push-rod and the depressing-lever.

Similar numerals of reference indicate corresponding parts in all the figures of the drawings.

35 The casing or frame in which the operating parts of the attachment embodying my invention are mounted is parallel-sided and consists of parallel side plates 1, preferably cut away or scrolled to reduce the weight thereof, 40 and spacing-blocks 2, interposed at terminal and intermediate points between the side plates to maintain them in their proper relative positions, said side plates being provided at their lower edges with outwardly-turned 45 securing-ears 3, through which may extend screws for holding the attachment in the longitudinal kerf or groove formed in the edge of a door. Obviously this kerf or groove in the door must be of such a width and depth 50 as to receive and snugly fit the frame or casing to avoid rattling or displacement when the door is jarred.

Snugly fitted between and guided vertically by the inner or opposing faces of the side plates 1 is a drop strip or bar 4, terminating 55 flush with the ends of the side plates 1, and hence flush with the side edges of the door to which the attachment is applied, the length of the frame or casing of the attachment being equal with that of the edge of the door in which 60 it is countersunk. Lifting or return springs 7 are secured at their outer ends to the drop strip or bar near its terminals and are engaged at their inner ends with studs or cross-pins 8 located between the planes of the side plates 65 and supported in fixed positions thereby, and the upward movement of the drop-bar when released for actuation by the return-springs 7 is limited by the terminal spacing-blocks 2, under which the extremities of said drop-bar 70 extend, as shown in Fig. 1. Endwise displacement of the drop-bar is prevented without the use of auxiliary guides or equivalent means by coiling the extremity of one of the springs 7 around the stud or cross-pin 8 upon 75 which it has a bearing; but in order that the drop-bar may be free to tilt to occupy a position with one extremity lower than the other, whereby it may properly bear upon an inclined surface or a surface disposed slightly 80 out of parallelism with the lower edge of the door, the inner end of the other lifting-spring 7 merely extends over and bears upon the upper side of its supporting stud or cross-pin 8. 85

In order that inequalities in the surface of the floor or sill may not interfere with the proper bearing of the strip, and hence the efficient exclusion of draft, the lower edge of the drop-bar is preferably provided with a 90 yielding or compressible bearing-strip or extension 5 of rubber, felt, or equivalent material, having a tongue or lip 6 fitted in a groove in the lower edge of the drop-bar, as shown in Fig. 3 and in dotted lines in Fig. 1. 95

Mounted between the planes of the side plates 1, above the upper edge of the drop-bar, is a bell-crank lever 9, having a long arm to bear terminally upon the upper edge of the drop-bar at an intermediate point approximately midway between the extremities of the drop-bar and having a short arm extending upwardly and provided with a seat, in which is loosely fitted a thimble 10, said thim- 105

ble being free to rock in a vertical plane in the seat of the lever and also to move axially or allow swinging movement of the lever independently thereof. Fitted for sliding movement in the bore of the thimble is a push-rod 11, extending through a guide-opening 12 in one of the terminal spacing-blocks 2 for contact with an adjustable stop 15 arranged in the frame or jamb of the door in the path of 10 the extremity of the push-rod as the door is swung to its closed position.

Coiled upon the push-rod between a collar 14 thereon and the contiguous flanged end of the thimble 10 and bearing terminally upon 15 said collar and flange is a push-rod-operating or return spring 13, held from displacement in one direction with relation to the thimble by means of a pin or equivalent device arranged therein beyond the extremity of said 20 thimble and obviously held from displacement in the opposite direction by the spring, while capable of independent sliding movement through the thimble in opposition to the tension of said spring. Thus as the door is 25 closed the extremity of the push-rod comes into contact with the adjustable stop 15 and forces the push-rod inwardly or toward the free edge of the door, thus applying pressure to the short arm of the depressing-lever 9 and 30 causing it to depress the drop-bar against the tension of its supporting-springs 7. As the parts are thus operated the thimble 10 is allowed to rock in its seat in the depressing-lever to avoid straining the push-rod trans- 35 versely and to maintain a suitable bearing for the contiguous end of the spring 13, and should the drop-bar or the elastic strip thereon meet an obstruction of any considerable size the spring 13 will yield to avoid straining the 40 parts. Said spring 13 by its pressure through the thimble upon the short arm of the depressing-lever holds the drop-bar with its elastic strip in yielding contact with the sill or the surface of the floor below the lower edge of 45 the door. Obviously a sill may be omitted where a strip of this class is used and thus an obstacle common in doorways may be avoided. For outside house-doors, however, it is prefer- 50 able to use a sill to serve as a water-shed, as in the ordinary practice.

Various changes in the form, proportion,

and the minor details of construction may be resorted to without departing from the spirit or sacrificing any of the advantages of this invention.

Having described my invention, what I claim is—

1. A weather-strip having a drop-bar, return-springs attached to said bar and engaged with fixed supporting-pins, the extremity of 60 one of said springs being coiled around its supporting-pin to hold the bar from endwise displacement, and the extremity of the other spring having a sliding bearing upon its supporting-pin to allow tilting movement of the 65 bar, and depressing devices having means for applying downward pressure to the drop-bar at an intermediate point, substantially as specified.

2. The herein-described weather-strip attachment for doors, the same comprising a parallel-sided frame or casing consisting of parallel side plates and interposed terminal and intermediate spacing-blocks, a drop-bar fitted snugly between and guided for vertical 75 movement by the opposing faces of said side plates and terminally flush with the ends of said side plates, lifting-springs attached at their outer ends to the drop-bar and bearing at their inner ends upon cross-pins connecting 80 the side plates of the frame, one of said springs being engaged with its cross-pin to prevent endwise displacement of the drop-bar, and the upward movement of the drop-bar being limited by the said terminal spacing-blocks, 85 a depressing-lever, and a push-bar having a yielding connection with the depressing-lever, to apply pressure therethrough to the drop-bar, all being mounted upon, and between the planes of the opposing faces of, the side 90 plates of the frame, for simultaneous insertion therewith into a longitudinal kerf or groove of a door edge, substantially as specified.

In testimony that I claim the foregoing as 95 my own I have hereto affixed my signature in the presence of two witnesses.

CLARENCE McCLELLAN EVELETH.
